UNITED STATES PATENT OFFICE.

LOUIS W. WITRY, OF WATERLOO, IOWA, ASSIGNOR TO WATERLOO GASOLINE ENGINE COMPANY, OF WATERLOO, IOWA.

DEVICE FOR TURNING CRANK-PINS ON ENGINE-SHAFTS.

1,045,239.

Specification of Letters Patent.

Patented Nov. 26, 1912.

Application filed October 2, 1911. Serial No. 652,317.

To all whom it may concern:

Be it known that I, LOUIS W. WITRY, a citizen of the United States of America, and a resident of Waterloo, Blackhawk county, Iowa, have invented certain new and useful Improvements in Devices for Turning Crank-Pins on Engine-Shafts, of which the following is a specification.

My invention relates to improvements in devices for turning crank-pins on engine-shafts, and the object of my improvement is to provide means capable of use on an ordinary engine-lathe which will receive engine cranks of differing dimensions, and which may be used to turn the crank-pins thereof quickly, truly and with the proper finish and design. This object I have accomplished by the means which are hereinafter described and claimed, and which are illustrated in the accompanying drawings, in which:

Figure 1 is an elevation of an engine-lathe equipped with my improved device for turning the crank-pin of an engine-shaft. Fig. 2 is a slightly enlarged end elevation of the pair of cutting-tools used with my device. Fig. 3 is an end-elevation in detail of the end of the journal-end holding-body which has the crank-arm clamping-means mounted thereon. Fig. 4 is a side elevation of said journal-end holding-body, showing an engine-shaft journal-end removably secured in the seats therein. Fig. 5 is a similar view of said holding-body, the holding-body being turned one quarter around. Fig. 6 is a transverse section of said holding-body taken on the line $x-x$ of Fig. 4 and looking toward the left. Fig. 7 is a transverse section of said holding-body taken on the line $y-y$ of said Fig. 4. Similar numerals of reference designate corresponding parts throughout the several views.

The numeral 48 designates an engine-lathe on which my improved device for turning the crank-pin of an engine-shaft is removably mounted. This device comprises a holding-body for the journal-end of an engine crank-shaft, and cutting-devices appropriate for turning the crank-pin of the shaft into a true finished shape. The holding-body comprises vertical spaced apart parallel disks 1 and 2, connected by integral parts set at right-angles to each other, as shown at the webs 3, 4, 5 and 6. The webs

3 and 4 extend diametrically across the heads lying therebetween, while the other heads are offset a little from each other perpendicularly to the other said webs. The webs 3 and 4 serve only to strengthen the holding-body, but the other webs are supplied with similarly formed but differently sized alined seats, suitable to receive the journal-ends of crank-shafts of differing diameters. The seats in these webs may have bearings 7 and 16, and 8 and 22 respectively, which may be either fixed or removable, and each bearing is trough-shaped in cross-section, as best shown in Figs. 6 and 7. The bearings 7 in the web 5, and 8 in the web 6, have cross-plates 11 and 12 respectively, which are removably secured over said bearings by means of the screws 13 and 14. These cross-plates serve to secure the journal-ends in the bearings, and the journal-end 23 is secured also by means of a set-screw 10 seated in the web 5 and engaging it. The bearing 8 has a similar set-screw 9 for a like purpose. The disk 1 is bolted to the face-plate 49 of said lathe by means of bolts 15, axially in alinement therewith. The webs 5 and 6 have at their right-hand ends similar expansions 19 and 20 respectively, which contain the bearings 16 and 22, and set-screws 17 and 21 respectively serve to secure journal-ends in said bearings removably.

The numeral 38 designates a ring-bearing which surrounds the disk 2 and is spaced apart therefrom all around, and being concave within, contains bearing-blocks 39 equidistantly placed about said disk and adapted to bear against the edge of the latter. The bearing-blocks 39 are movable toward said disk and adjusted by means of set-screws 40 to properly center said disk.

The clamping-means on the right-hand face of the disk 2 comprises a pair of fixed blocks 42 and 43, spaced apart and secured to the disk by means of screws, the space left between said blocks being sufficient not only to receive therebetween crank-pin arms of different widths, but also permit of some adjustment of said arms 25 to bring the crank-pin 24 into axial alinement with said holding-body on the lathe. The numerals 44 and 45 designate sliding-blocks movable in grooved seats in the fixed blocks 42 and 43, and whose inner ends are oppositely located in alinement across the diameter of

the disk 2 and adapted to adjustably clamp opposite sides of a crank-arm 25 seated between them. The adjustment of said sliding blocks is made by means of set-screws 5 46 and 47 working through the blocks 42 and 43 respectively against them. When the journal-end of a crank-shaft 23 has been passed into whichever of the trough-shaped openings in the disk 2 which is fitted to receive it and then secured to said holding-body by the means described so that its crank-pin 24 is truly alined with said holding-body, the crank-pin is in a position suitable for rotation to be shaped truly into the 10 required form by means of the following described cutting-tools and appliances.

The numeral 36 designates a base-block adapted to be mounted on the lathe-frame to the right-hand of the ring-bearing 38, the latter being also mounted on said lathe-frame. The base-block 36 adjustably supports a body 35 upon which are transversely spaced apart uprights 28 and 29 secured to it by bolts 33 and 34 respectively. The upright 28 has on its inner face a cutter-tool 26 secured thereon adjustably by means of adjusting screws 30 and 31. The other upright 29 has a cutter-tool 27 secured on its inner face adjustably by means of an adjusting-screw 32. Spindle-arms 37 may be used to adjust the position of said parts transversely on the lathe-bed. When the tool 26 is used, it gives a rough-cut to the crank-pin 24, and this operation is succeeded by the use of the cutting-tool 27 which finishes the crank-pin to the smooth desired form.

The said device accurately performs the required duty in a minimum time, and perfects the crank-pins with a great saving of 40 labor.

It is to be understood that variations of said device are covered by the scope of and included within the principle of this invention.

Having described my invention, what I claim as new, and desire to secure by Letters Patent, is:

1. In combination, a face-plate, an end-supporting body, a body having a plurality of eccentrically-located seats of differing sizes for holding the journal-ends of crank-shafts of different dimensions detachably secured between said face-plate and said end-supporting body, said seats being located at appropriate distances from the axis of said body, clamping-means on said body adapted to adjustably secure a crank-pin in axial alinement with said body, and cutting-means movable into cutting engagement with a crank-pin so held by said clamping-means and adapted to trim it into a desired form.

2. In combination, a face-plate, a ring-shaped coaxial end-supporting body, a body having a plurality of eccentrically-located 65 seats of differing sizes for holding the jour-

nal-ends of crank-shafts of different dimensions detachably secured centrally between said face-plate and said ring-shaped end supporting body and extending centrally into the latter, said seats being located at appropriate distances from the axis of said body, means for detachably securing a journal-end in either of said seats adapted to receive it, clamping-means on said body adapted to adjustably secure a crank-pin in axial alinement with said body, and a plurality of cutters movable toward said crank-pin and adapted to impart to it a desired form.

3. In combination, a face-plate, an end-supporting body coaxial with and spaced apart therefrom, a holding-body detachably connected to and between said supporting-body and said face-plate and having an eccentrically-located seat for a crank-shaft 80 journal-end, with means for detachably securing said journal-end in said seat.

4. In combination, a face-plate, a ring-shaped end-supporting body coaxial with and spaced apart from said face-plate, a holding-body having one end detachably secured to said face-plate and its other end projected within the said end-supporting body, means for detachably and adjustably securing said holding-body within said end-supporting body, said holding-body having a seat for the journal-end of a crank-shaft located without the axis of said parts, and securing-means for holding a journal-end 95 detachably in said seat.

5. In combination, a face-plate, a ring-shaped end-supporting body coaxial with and spaced apart from said face-plate, a holding-body having one end detachably secured centrally to said face-plate and its other end projected within the said end-supporting body centrally, means for detachably securing said holding-body within said end-supporting body, comprising set-screws located to work through the latter to engage said holding-body adjustably, said holding-body having a seat for the journal-end of a crank-shaft located eccentrically without the axis of said supporting-bodies, and means for detachably securing a journal-end in said seat.

6. In combination, a face-plate, a ring-shaped end-supporting body coaxial and spaced apart therefrom, and a holding-body comprising oppositely arranged integral 120 webs coaxial therewith and secured centrally to said face-plate and end-supporting body, oppositely-projecting webs of said holding-body being provided with seats for crank-shaft journal-ends located eccentrically at 125 different radial distances from the axis of said parts, and means for securing a journal-end in either of said seats.

7. In combination, a face-plate, a ring-shaped end-supporting body coaxial with 130

and spaced apart from said face-plate, a holding-body located between said face-plate and end-supporting body, secured centrally to the former and projected into the latter 5 centrally, means for adjustably securing said holding-body within said end-supporting body, said holding-body comprising integral webs located on opposite sides of the axis of said parts and offset from each other, 10 and seats for crank-shaft journal-ends located integrally in opposite sides of said offset webs, means for detachably securing journal-ends in said seats, and means for adjusting the position of the crank-shaft, at- 15 tached to said holding-body, comprising oppositely located clamping-members adjustably seated on said holding-body.

8. In combination, a face-plate, a ring-shaped end-supporting body, a holding-body 20 secured between said parts centrally and

provided with a seat for a crank-shaft journal-end, means for detachably securing a journal-end in said seat, oppositely-located slide-ways on the end of said holding-body which is connected to said end-supporting 25 body, clamping-bodies in said slide-ways adapted to engage the crank-pin part of an engine-shaft between them, and adjusting-screws connecting said slide-ways and clamping-members adapted to actuate said mem- 30 bers to and from each other to cause such a crank-pin to become centered with the axis of said holding-parts.

Signed at Waterloo, Iowa, this 14th day of Sept., 1911.

LOUIS W. WITRY.
